UNITED STATES PATENT OFFICE.

HARRY M. PFLAGER, OF ST. LOUIS, MISSOURI, ASSIGNOR TO COMMONWEALTH STEEL COMPANY, OF ST. LOUIS, MISSOURI, A CORPORATION OF NEW JERSEY.

AIR-BRAKE-CYLINDER ATTACHMENT TO RAILROAD-CARS OR THE LIKE.

No. 917,891.

Specification of Letters Patent. Patented April 13, 1909.

Application filed September 14, 1908. Serial No. 452,902.

To all whom it may concern:

Be it known that I, HARRY M. PFLAGER, a citizen of the United States, residing at St. Louis, in the State of Missouri, have invented 5 a new and useful Improvement in Air-Brake-Cylinder Attachments to Railroad-Cars or the Like, of which the following is a specification.

My invention relates to the block or suspension bracket for the attachment of the air-brake cylinder to the underside of a railroad car or analogous vehicle, this attachment ordinarily consisting of a wood block or built up frame of wrought steel plates, 15 which is heavy and cumbersome and occupies considerable space, and my invention has for its object to provide a strong, light, rigid, and compact integral structure for the purpose.

It consists in features of novelty as herein-after described and claimed, reference being had to the accompanying drawing forming part of this specification, whereon,

Figure 1, is a top plan view of my improved 25 air-brake cylinder attachment applied to the underside of the longitudinal sills (broken away) of a railroad car; Fig. 2, a vertical transverse section through the sills on line 2, 2, in Fig. 1, showing the air-brake cylinder attachment in end elevation, and Fig. 3, a perspective view of the attachment detached.

Like letters and numerals of reference denote like parts in all the figures.

35 *a* represents my improved air-brake cylinder attachment which is composed preferably, of cast steel integral throughout and comprises in the present case preferably, two parallel spaced apart L-shaped bars *b* having 40 their lower legs 1 in the same horizontal plane and their upright legs 2 inward and opposite to each other, the horizontal leg 1 of each bar *b* at a suitable distance from each end thereof being curved upward to a level 45 with the edge of the upright leg 2 and formed thence to the said end with a straight flat portion 1', the upright leg 2 terminating at the said curvatures of the horizontal leg 1.

The bars *b* are united together at a suitable

distance from their respective ends by preferably, two parallel spaced apart L-shaped bars *c* which are at right angles and similarly arranged to the bars *b*, except that the flat end portions 1' of the latter are eliminated and the upwardly curved portions of their 50 lower horizontal legs 3 terminated at and uniting with the upright legs 4 of the bars *c*, the top of the upright legs 4 of the bars *c*, the whole forming a strong, light, and compact 55 frame through which the metal is distributed to the best advantage for obtaining the necessary rigidity within the limit of depth or thickness allowed to the frame thereat for maintaining the normal standard level of the air-brake 60 cylinder *d* which in assembling the parts is arranged between and fixed to the underside of the lower horizontal legs 3 of the bars *c* longitudinally therewith, by bolts 5, the bars *b* extending transversely to the car, preferably 65 between and beneath the longitudinal sills *e* to which the flat end portions 1' of the bars *b* are fixed by bolts 6, all as indicated by dotted lines. Or the bars *b* may be otherwise adapted at their end portions for attachment of the frame to any other suitable 70 part of the car underframe according to the contour and material of the latter.

A great advantage of my invention is, that by substituting a cast metal integral structure of special design as to strains, for the ordinary wood block or built up framework of iron with its fastenings, the stability of the air-brake cylinder is positively insured with less weight of material and liability to work 80 loose under varying conditions of load.

What I claim as my invention and desire to secure by Letters Patent is:—

A cast metal air-brake cylinder attachment to a railroad car, having all its parts 90 integral and comprising two opposite parallel spaced apart L-shaped bars having their horizontal legs respectively, curved upward near each end, and thence to the said end formed horizontally flush with the edge of 95 the upright leg of the bar, and adapted thereat to be fixed to the underframe of the car-body, and two opposite parallel spaced

apart L-shaped bars having their upright legs at right angles to, and uniting with the corresponding legs of the first named bars and having their horizontal legs curved upward near each end to their junction with the upright legs of the first named bars, and adapted on their underside for the attachment thereto of the said cylinder, substantially as described.

HARRY M. PFLAGER.
